(57) **CLAIM**

The ornamental design for a pickleball paddle, as shown and described.

DESCRIPTION

FIG. 1 is a top perspective view of a pickleball paddle showing the claimed design;

FIG. 2 is a bottom perspective view thereof;

FIG. 3 is a front elevation view thereof;

FIG. 4 is a left-side elevation view thereof, an undisclosed right-side elevation view being a mirror image of the left-side elevation view;

FIG. 5 is a bottom view thereof;

FIG. 6 is a top view thereof.

FIG. 7 is a top perspective view of the pickleball paddle with a broken line environment showing a paddle of a different shape;

FIG. 8 is a bottom perspective view thereof;

FIG. 9 is a front elevation view thereof;

FIG. 10 is a left-side elevation view thereof, an undisclosed right-side elevation view being a mirror image of the left-side elevation view;

FIG. 11 is a bottom view thereof;

FIG. 12 is a top view thereof.

FIG. 13 is a top perspective view of the pickleball paddle with a broken line environment showing a paddle of a different shape;

FIG. 14 is a bottom perspective view thereof;

FIG. 15 is a front elevation view thereof;

FIG. 16 is a left-side elevation view thereof, an undisclosed right-side elevation view being a mirror image of the left-side elevation view;

FIG. 17 is a bottom view thereof; and,

FIG. 18 is a top view thereof.

Broken lines in the figures illustrate portions of the pickleball paddle that form no part of the claimed design.

1 Claim, 15 Drawing Sheets
